UNITED STATES PATENT OFFICE.

GEORGE HENRY ELWELL, OF BOSTON, MASSACHUSETTS.

SAFETY CATCH-LATCH.

1,235,885.

Specification of Letters Patent.

Patented Aug. 7, 1917.

Application filed October 20, 1914. Serial No. 867,649.

To all whom it may concern:

Be it known that I, GEORGE HENRY ELWELL, of Boston, in the county of Suffolk and State of Massachusetts, have invented 5 certain new and useful Improvements in Safety Catch-Latches, of which the following is a specification.

My invention relates to safety door-holding means for doors of motor cars and the 10 like and has for its object to provide an improved means by which a door when in its closed position is rendered positively locked against accidental opening.

Further objects of this invention are: to 15 provide a lock that will allow for the elasticity of a motor car body without lessening its efficiency as a safety device, and to provide a lock having a double action bolt, actuated, upon the closing of the door entirely 20 by the striker-plate and controlled by a single and familiar operation to open the door.

A further object of my invention is to 25 provide a door-holding means having a combined bolt and hook, the hook pointing toward the striker-plate as the door carrying the door-holding means is about to close.

A further object of the invention is to provide a combined bolt and hook lock, in which 30 the hook is moved laterally by engagement with the striker-plate or by the rearward movement of an operating lever independently of the backward movement of the bolt.

With these and other objects in view, as 35 will more fully hereinafter appear, the invention consists in certain novel features of construction and arrangement of parts, hereinafter described, illustrated in the accompanying drawings, and particularly pointed 40 out wherein patentable novelty is claimed for certain features of the device, it being understood that within the scope of what hereinafter thus is claimed, various changes in form, proportion, size and minor details 45 of the construction may be made without departing from the spirit or modifying any of the advantages of the invention.

The following is a description of an embodiment of my invention, reference being 50 had to the accompanying drawings:

In the accompanying drawings: Figure 1 is an interior elevation of the device, as fully described.

Fig. 2 is a detailed end view of the bolt-member operatively held by a T-rivet. 55

Fig. 3 is a top view of device as fully described.

Fig. 4 is a front view of a compound lever forming part thereof.

Fig. 5 is a top view of a modified form 60 employing a simple lever.

Similar numerals of reference are employed to indicate corresponding parts throughout the several figures of the drawing. 65

Referring more particularly to the drawings, a supporting plate 1 with one end bent at convenient angle to form face 2 and thus provide an incasement. A striker-plate 2' opposes this face-plate when the device 70 is upon a closed door. The face 2 is provided with a guiding perforation 3 for a bolt-head passage from within said incasement. The locking-bolt consists of a latch-bolt 4 having a two-part body portion, held 75 by guides upon said base-plate, and a spring

catch-member 5 carried thereby, whose end projects laterally from the bolt-head 6 so as to form a hook and is normally maintained in that position by the action of spring- 80 means 7, as shown in Figs. 3 and 5. The outer ends of the body portion or the catch member, or preferably of both, are beveled

so that they will be retracted longitudinally upon engagement with the striker-plate. 85 The hook of the catch member projects from the beveled side of the body portion and points toward the striker plate as it approaches the same. The latch-bolt 4 is maintained on said supporting plate by the engagement of bolt-head 6 in perforation 3 in

face 2 of the said incasement and by the T-rivet 8 operatively engaging the rear ends of said bolt parts, as shown in Figs. 1 and 2, and said latch-bolt is normally maintained 90 in its projected position by spring-means 9. The latch-bolt has two parallel parts and rivets 10 and 11 fasten these bolt parts together. Rivet 10 also serves as an axis upon

which said spring-catch 5 operates, while 100 rivet 11 limits the backward movement of the catch 5. When sufficient pressure is placed upon any forward portion of said spring-catch 5, that member retires within the lateral confines of bolt-latch 4 enabling 105

bolt-latch-head 6 to be drawn or forced into

incasement; otherwise spring-catch 5 left in its normal position becomes a barrier, not only preventing the bolt-latch-head 6 from so retiring but when said spring-catch 5 is likewise engaged behind the striker-plate 2' spring-catch 5 is interlocked therewith and thereby forms the safety feature of this device. To provide for the racking or giving due to the elasticity of a motor car body, 10 spring-catch 5 is so relatively arranged with said striker-plate that when said latch-bolt-head 6 makes holding engagement with the striker-plate the hook of the catch 5 lies well beyond the inner surface of the striker-plate, engagement therewith in this form being intended only upon accidental separation of the door and the body portion to which said device and the striker-plate are respectively attached.

20 The automatic function of the device is demonstrated when upon closing the door to which the device is attached the spring-catch 5 member of the latch-bolt engages the striker-plate causing pressure against

25 said spring-catch 5 and against its spring-action 7, sufficient to retire said spring-catch 5 within the lateral confines of latch-bolt-head 6, and thus bringing the latch-bolt-head 6 and the striker-plate into direct engagement, whereby the latch-bolt-head 6 is forced back into the incasement until the said door is in its fully closed position, when the latch-bolt 4 is released and springs into the striker-plate, spring catch-member 5 35 being held within the lateral confines of said latch-bolt-head 6 until passing into the striker-plate, when it, being released, springs to its normal position and behind the striker-plate.

40 To unlock and open the door to which said device is attached pressure must be exerted against the spring action of said spring-catch 5 sufficient to retire that spring-catch member within latch-bolt-head 45 6 before latch-bolt 4 may be withdrawn.

Any means of pressure against the spring action of said spring catch-member 5 may be adopted, but for the purpose of combining said means of pressure with the means for 50 withdrawing said latch-bolt 4 so that together they shall be controlled by one operation, I provide a lever which is made to operate in the well known manner, but before it engages the bolt body proper to withdraw 55 it, it is made to engage a laterally projecting shoulder 14 of said spring catch-member 5, creating the necessary pressure against the spring-action of said spring catch-member 5 and thereby retiring it, as aforesaid, and

60 permitting said lever 13 to next withdraw latch-bolt head 6 in the ordinary manner. The lever may be a simple lever as shown at 13 in Fig. 5. Because of the increased scope of operation of said lever 13, which is of 65 the second class, made necessary under the

aforesaid construction, lever 13 in Figs. 1 to 4 is provided with cam blade 16 which is pivoted to supporting plate 1 and constitutes a lever of the third class, the two simple levers constituting a compound lever. The 70 cam blade 16 is provided with elongated slot 17 intended for engagement with pin 18 with which lever 13 is provided as shown in Fig. 4. Lever 13 in this form normally lies directly at one side of shoulder 14 of 75 said spring catch-member 5 ready to engage a shoulder on the bolt-body proper as shown in Fig. 3. The upper end of lever 13 constitutes a handle and upon manually operating the lever 13, Fig. 1, cam blade 16 is 80 swung upon its pivot and its lower extremity is carried by said lever movement at a speed much greater than said lever 13, owing to its shorter radius, and engages shoulder 14 of spring catch-member 5 and operates 85 it before said lever 13 has withdrawn said latch-bolt 4 sufficiently to cause an engagement of said retiring spring-catch 5 with the striker-plate.

The operating lever is provided with a 90 spring 15, Fig. 1, to maintain it normally in a position ready to engage said shoulder 14 of said spring catch-member 5.

For the purpose of strengthening the construction of the latch-bolt, and to make unnecessary any preparation for lever-movement in the surface of the door, the supporting plate 1 may be struck up with a lever-chamber 19 as shown in Fig. 3, the chamber lying outside the general plane of the supporting plate.

The operation of the device is as follows: As a door carrying the holding device closes the beveled face on the hook member 5 engages the forward edge of the striker-plate 2' and the hook is thereby forced backward with a lateral movement. The beveled surfaces on the hook-member and the outer end of the body of the bolt then act to cause the bolt as a whole to move inwardly until 110 the door is shut, whereupon the bolt as a whole is moved outwardly by the spring 9 and thereafter the hook is projected laterally by the spring 7 so as to lie behind the striker-plate, locking the door to the striker-plate so that they cannot be pulled apart. In 115 opening the door the lever 13 is actuated in the ordinary manner. By its engagement with the projection 14 it retracts the hook laterally so as to withdraw it from behind the striker-plate and then by its engagement with the shoulder on the bolt body fully 120 retracts the bolt as a whole, so as to withdraw it from the opening in the striker-plate. In closing the door the bolt can be 125 retracted by the operation of the lever before the door is swung to if desired, in which case the beveled faces on the body and hook portions perform no functions. They are preferably present on one or both 130

of these members, however, so that the bolt will be retracted by the mere closing of the door.

What I claim is:

- 5 1. A door catch-latch bolt comprising an incasement, a latch bolt slidably mounted in said incasement, said bolt being provided with a beveled side head capable of being advanced through a guide with which said incasement is provided; said bolt being also provided with a spring pressed catch member pivotally mounted on said bolt, said catch member being provided at its free end with a hook shaped head laterally projecting from the beveled side of said bolt head; spring means to maintain said catch member in its projected position; and spring means exerted to maintain said bolt in its advanced position.
- 10 2. A door catch-latch bolt, comprising a proper incasement, a latch bolt slidably mounted within said incasement, said latch bolt comprising three sections the outer sections of which are provided with beveled heads fixed in parallel position one to the other, the middle section thereof forming an arm, pivotally mounted between said outer sections and provided at its free end with a hook shaped head capable of being projected laterally from between said beveled heads of said outer sections; spring means exerted to normally maintain said arm in its laterally projected position; and spring means exerted to advance and maintain said bolt in its advanced position.
- 15 3. A door automatic catch-latch comprising an incasement, a latch bolt slidably mounted within said incasement, said bolt being provided with a beveled head capable of being advanced through a guide with which said incasement is provided, said bolt carrying a spring pressed catch member; spring means exerted to normally maintain said bolt in its advanced position; spring means exerted to normally maintain said catch member projected laterally from the beveled side of said bolt head for engagement behind the striker plate, permitting the automatic retirement of said catch member and said latch bolt against the action of their respective spring means upon their consecutive engagements with the striker plate; and manually operative means to retire said catch member and said latch bolt.
- 20 4. A door automatic safety catch-latch comprising an incasement, a latch bolt slidably mounted within said incasement, said bolt being provided with a beveled head capable of being advanced through a guide with which said incasement is provided, said bolt carrying a spring pressed catch member provided with a hook shaped portion; spring means exerted to normally maintain said bolt in its advanced position; spring
- means exerted to normally maintain said catch member projected laterally from the beveled side of said bolt head, permitting the automatic retirement of said catch member and said latch bolt against the action of their respective spring means when in consecutive engagement with the striker plate; and manually operative means to retire said catch member and said latch bolt, said operative means comprising a lever pivotally mounted within said incasement for consecutive engagements with said catch member and said latch bolt.
- 25 5. In a safety catch comprising a latch-mechanism and striker-plate for making holding engagement, the combination of a base-plate adapted to be mounted upon a swinging door, a hook catch movably mounted on said base-plate, and having a beveled face adapted to engage said striker-plate as the door closes, the nose of the hook being turned inwardly toward the striker-plate when the door is open, and a striker-plate having an outwardly extending portion behind which the nose of said hook catch rests when the door is closed.
- 30 6. A door-catch-bolt for making holding engagement with a striker-plate comprising a base-plate, a bolt slidably mounted on said base-plate and consisting of a sliding member having a body portion held by guides on said base-plate, and a catch member movably connected to said body portion, said catch member having a hook-shaped head, the nose of the hook pointing toward said striker-plate when approaching the same, the end of one of said members having a beveled face adapted to engage said striker-plate, said bolt and hook when retracted normally tending to move outwardly and the hook to move laterally relatively to said sliding member, and means for manually retracting said catch member laterally and said bolt longitudinally.
- 35 7. A door catch-bolt for making holding engagement with a striker-plate comprising a base-plate, a normally longitudinally projected bolt slidably mounted on said base plate and consisting of a sliding member having a body portion held by guides on said base plate and a catch-member movably connected to said body portion and normally laterally projected, said catch-member having a hook-shaped head, the nose of the hook pointing toward said striker-plate when approaching the same, the end of one of said members having a beveled face adapted to engage said striker-plate, and means for manually retracting said catch-member laterally and said bolt longitudinally.
- 40 8. A door catch-bolt for making holding engagement with a striker-plate comprising a base plate, a normally longitudinally projected bolt slidably mounted on said base plate and consisting of a sliding member

having a body portion held by guides on said base plate and a catch member movably connected to said body portion and normally laterally projected, said catch member having a hook shaped head, the nose of the hook pointing toward said striker-plate when approaching the same, the outer ends of both of said members having beveled faces adapted to engage said striker-plate, and means 10 for manually retracting said catch-member laterally and said bolt longitudinally.

9. A door catch-bolt for making holding engagement with a striker-plate comprising a base plate, a bolt slidably mounted thereon 15 and consisting of a body portion and a catch member pivotally connected to said body portion, said catch member having a hook shaped head whose nose points toward said striker-plate when approaching the same, 20 and a retracting lever, said bolt having laterally projecting means located in the path of said lever upon which said lever acts to retract said hook laterally and said bolt longitudinally, said bolt having a beveled 25 face adapted to be engaged by said striker-plate.

10. A door catch-bolt for making holding engagement with a striker-plate comprising a base plate, a normally longitudinally projected bolt slidably mounted on said base 30 plate and consisting of a body portion and a catch member pivotally connected to said body portion and normally laterally projected, said catch member having a hook 35 shaped head, the nose of the hook pointed toward said striker-plate when approaching the same and a lateral projection located between its hook-shaped head and pivot, said bolt having an abutment, and a manu- 40 ally operative lever engaging said projection and abutment so as to retract said hook laterally and retract said bolt longitudinally,

said bolt having a beveled face adapted to be engaged by said striker-plate.

11. A door catch-bolt for making holding engagement with a striker-plate comprising a base plate, a normally longitudinally projected bolt slidably mounted on said base plate and consisting of a body portion and a catch member pivotally connected to said body portion normally laterally projected, 45 said catch-member having a hook-shaped head, the nose of the hook pointing toward said striker-plate when approaching the same and a lateral projection located between its hook-shaped head and pivot, said bolt having an abutment, and a manually operative lever engaging said projection and abutment so as to retract said hook laterally and retract said bolt longitudinally, 50 said bolt having a beveled face adapted to be engaged by said striker-plate.

12. A door catch-bolt for making holding engagement with a striker-plate comprising a base plate, a bolt slidably mounted thereon 55 and consisting of a body portion and a catch member pivotally connected to said body portion, said catch-member having a hook-shaped head whose nose points toward said striker-plate when approaching the same, 60 and a compound retracting lever, said latch-bolt having a laterally projecting surface on said catch-member and an abutment adapted to be engaged by said lever, said compound lever consisting of two simple levers, one 65 of which constitutes a handle and the other 70 of which engages said laterally projecting surface.

In testimony whereof I have affixed my signature, in presence of two witnesses.

GEORGE HENRY ELWELL.
